UNITED STATES PATENT OFFICE.

TROY D. SMEDLEY, OF WATERLOO, IOWA.

PLANT MARKER.

Application filed August 12, 1927. Serial No. 212,474.

My invention relates to improvements in plant markers, and the object of my improvement is to supply florists and others with a device of this class provided with an inscription receiving member adapted for being shifted from an inscription covered position to an inscription exhibiting position.

This object I have achieved successfully by the device which is exemplified in the accompanying drawings, and which is described and claimed herein. In said drawings, Fig. 1 is a front elevation of the device with the hinged flap thereof in its lowered position, and Fig. 2 is a like elevation showing the flap raised and swung over to exhibit an inscribed card detachably mounted thereon. Fig. 3 is an elevation of the opposite face of the device with the flap depending, and Fig. 4 is a side elevation of the device with its parts in the same relative positions as shown in said Fig. 3. Fig. 5 is a like side elevation showing the flap swung upwardly to a card exhibiting position. Fig. 6 is a perspective view of the device with its flap extended in said exhibiting position.

My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described and defined in the claims without attempting to show all of the various forms and modifications in which my invention might be embodied.

My improved device is particularly adapted for use by florists and gardeners, but with slight modifications within the power of anyone skilled in the art or even others, may be changed within the scope of my claims to be used for other or analogical purposes.

In the embodiment of my invention illustrated, the numeral 1 denotes a stake preferably pressed in longitudinally troughed or channeled shape with edge flanges 2 along its opposite longitudinal edges, and also preferably the stake is diminished gradually toward its lower end and also terminally pointed at 3 to permit of its easy insertion in the soil in a substantially vertical position. Between the upper parts 4 of the side

flanges the top part of the stake 1 is cut away at 5 leaving a medial prop part 6 standing for a purpose to be disclosed. Just above the top edge of the prop 6 the flange parts 4 are apertured in horizontal and transverse alignment circularly at 7 to receive the short pintle parts 9 of a flap 8 rockingly.

The flap may be of any suitable shape for the particular function of receiving inscriptions thereon, or on a card to be detachably mounted thereon. That shown has a rectangular form and has on its under face and along its longitudinal edges bent over slide-way flanges 10 which may be used to slidably receive a card 12 therein detachably to receive on its exposed face entries, such as the name of a plant and the entrance ends of the flanges pinched down at 11 to prevent endwise escape of the card. The outer ends of the flanges 10 may be pinched down upon the flap to prevent escape of the card 12. As the flap 8 is rectangular and sufficiently wide to swing closely between the flange parts 4, the stake body 1 diminishing downwardly, when the flap is swung to its depending position, it spans the flanges 2 to ride terminally thereon in an inclined position relatively to the substantially vertical stake 1. This protects the card 12 and its inscription, as the card is thus covered from the sunlight or the action of rain, the inclined position of the flap facilitating drainage. When the flap 8 is by a flip of the finger swung upwardly across the top of the stake, it comes to rest and is supported in a substantially horizontal position upon the prop part 6, as the latter is set off to the rear from the pintles 9. In this position the outer face of the card 12 is exposed upwardly, the passerby being enabled to read its inscription at a glance, and then being enabled to flip the flap back to its depending position.

As the device is simple in construction, and cheaply made in large lots by stamping processes, it is of economical use by plant growers, for it may be stored after each season's use and kept for many years when made of metal treated to prevent corrosion.

Having described my invention, what I claim as new, and desire to secure by Letters Patent, is:

1. A device of the character described, comprising a stake diminished downwardly and having longitudinal edge flanges, and a flap hinged inclinedly to and between the

upper parts of said flanges to swing vertically and wide enough to span and ride upon said flanges in an inclined position relative to the stake, said flap having card holding means on its under inclined face.

2. A device of the character described, comprising a stake diminished downwardly having side flanges with lower ends beveled to the stake termination at each side, the stake 10 termination being pointed therefrom and a flap hinged upon said stake to be swung from a sign exhibiting to a sign concealing position astride said flanges, said flap having edge engaging parts to detachably receive a 15 sign member.

3. A device of the character described, comprising a longitudinally channeled and downwardly diminished stake having its

upper part excised between the flanged sides thereof at the ends of an upwardly extending prop part, a flap having side card receiving flanges on its under face and along its longitudinal edges bent toward each other to detachably slidably receive an inscription exhibiting device, said flap when 20 swung downwardly being inclined to conceal the inscription exhibiting device thereunder and being supported hinged on the flanged sides of the stake at an inclined position, and when swung upwardly across 25 the top of the stake being supported on said prop part to exhibit upwardly said exhibiting device.

In testimony whereof I affix my signature.

TROY D. SMEDLEY.
